TRUCK FOR HANDLING CLOTH

David Gessner, Worcester, Mass.

Application February 15, 1932, Serial No. 593,063

2 Claims. (Cl. 280—49)

This invention relates to the handling of cloth in successive finishing operations. In such operations, it is frequently desirable, and in fact necessary, that the cloth pass through successive machines in the same direction and with the same end of the piece of cloth entering first into each of the successive machines.

As the cloth leaves each machine, it is usually deposited in a folded pile on a truck or other support. In order that the same end of the cloth may enter first into the succeeding machine, it has been necessary to refold the cloth in a reverse pile as a separate operation, or to turn the pile of folded cloth bottom side up. This has been a heavy and laborious manual operation, during which the folded cloth frequently became more or less disarranged, which often caused trouble in the next operation.

It is the object of my present invention to provide means by which a pile of folded cloth may be quickly and easily inverted and without disarrangement of the cloth.

A further object is to provide mechanical means by which a single operator may easily invert or reverse a large pile of heavy wet cloth without assistance and without disarranging the folds.

In the preferred form of the invention, I embody my improvements in a special truck construction by which the cloth may be moved about from place to place as well as being inverted before feeding to the next succeeding machine.

My invention further relates to arrangements and combinations of parts which will be hereinafter described and more particularly pointed out in the appended claims.

A preferred form of the invention is shown in the drawings, in which

Fig. 1 is a side elevation of a truck embodying my improvements;

Fig. 2 is an end view thereof, looking in the direction of the arrow 2 in Fig. 1;

Fig. 3 is a sectional end elevation, taken along the line 3—3 in Fig. 1;

Fig. 4 is a view similar to Fig. 3 but showing the parts in a different position;

Fig. 5 is a detail sectional view, taken along the line 5—5 in Fig. 1, and

Fig. 6 is an enlarged side elevation of a fastening device to be described.

Referring to the drawings, my improved truck comprises a base or frame 10 having an axle 11 on which wheels 12 are pivoted. Straps 13 hold the axle 11 in position under the base or frame 10.

Rollers 14 are mounted in swiveled brackets

15 at the ends of the truck, but one only of these rollers 14 ordinarily engages the floor at the same time.

Stands or brackets 16 are mounted at the ends of the frame 10 and support bearings 17 and 18 for gudgeons 20 and 21 fixed in heads 22 and 23 which form the ends of the reversible truck body.

Rods or tubes 25 connect the heads 22 and 23 and provide supports for side frame members 27 to which spaced wooden slats 28 are secured in any suitable or convenient manner.

The side frame members 27 are provided with offset projections 30 at both ends thereof, to which cover frame members 32 are secured by locking pins 34 (Fig. 6). Additional spaced slats 35 are secured to the frame members 32.

The assembled frame members 32 and slats 35 constitute the cover portions A and B of the truck body. The parts A and B are of identical construction and either part may act as the bottom 75 while the other part acts as the top. Either part A or B may be released and moved to inoperative position as indicated in Figs. 3 and 4 by removing the locking pins 34 along one edge of the selected cover portion and swinging the released 80 cover portion around the locking pins 34 along its opposite edge as pivots.

The gudgeon 21 at the left-hand end of the truck (as viewed in Fig. 1) is extended beyond the bearing bracket 18 and is provided with a gear 40 engaged by a pinion 41 rotatably mounted in a bearing 42 (Fig. 2) supported by the stand or bracket 16. The gudgeon 21 is provided with opposed recesses 44 (Fig. 5), either one of which is adapted to receive a spring-pressed stud or 90 plunger 45 having a knob or handle 46 by which it may be raised to release the gudgeon.

Whenever the truck body is in either the position shown in Fig. 3 or the position shown in Fig. 4, the plunger 45 enters one of the recesses 95 44 and holds the truck body from accidental rotation. When, however, it is desired to reverse the truck body, the plunger 45 is raised to release the gudgeon 21, and the truck body may then be rotated by means of a handle 50 attached 100 to the pinion 41.

Having thus described the details of construction of my improved truck, the use and advantages thereof will be readily apparent. The truck will be placed at the delivery end of a finishing machine, with the cover part A open as indicated in Fig. 3, and the cloth C will then be deposited in uniform folds in the truck body by any usual folding and delivery mechanism.

After one or more pieces of cloth have been de- 110

5 posited in the truck body, the cover portion A is closed and secured by inserting the associated locking pins 34. The spring plunger 45 is then raised to release the gudgeon 21 and the operator quickly and easily reverses the truck body by turning the handle 50.

10 When the reverse position is reached, the plunger 45 snaps into locking position, after which the operator unlocks and opens the cover portion B, and the cloth C is then ready for removal, presenting the same end of the piece of cloth to the next machine as in the preceding machine, so that the cloth enters successive machines without reversal.

15 Furthermore, it will be noted that both cover portions A and B are closed and locked while the truck body is being reversed, so that there is no chance for the folds of cloth to be disarranged or to be in any way displaced during the inverting 20 operation.

25 While I have described my invention as embodied in a truck for handling cloth, it will be understood that the invention is also capable of more general application and can be used for handling any kind of material in which reversal between successive operations is desired.

30 Obviously, either cover part A or B may be removed entirely whenever desired, by taking out the locking pins along both edges.

35 Having thus described my invention and the advantages thereof, I do not wish to be limited to the details herein disclosed, otherwise than as set forth in the claims, but what I claim is:—

1. A truck for handling folded cloth or other sheet material comprising a supporting frame, a

body pivotally mounted in said frame and having removable cover portions at two opposed faces thereof, means to position said body with either cover portion uppermost, said body comprising a plurality of side frame members having spaced body slats mounted thereon and having offset end extensions, and detachable pivoting and securing means effective to secure each longitudinal edge of each cover portion to said end extensions of said side frame member.

80

2. A truck for handling folded cloth or other sheet material comprising a supporting frame having spaced up-standing bearing portions, an elongated rectangular body adapted to receive layers of folded cloth and having end gudgeons 85 rotatably supported in said bearing portions, end frames in which said gudgeons are mounted, connecting members extending longitudinally between said end frames and holding said frames in fixed spaced relation, side frame members mounted in spaced relation on said connecting members, a plurality of spaced slats mounted on said side frame members and forming the sides of said body, spaced cover frame members pivotally and detachably connected at both ends to the 90 ends of said side frame members, and slats mounted in spaced relation on said cover frame members, whereby a body is provided having spaced slatted sides and covers, said body being reversible on said supporting frame and each cover 95 being manually releasable along either longitudinal edge thereof and adapted for swinging movement about its opposite longitudinal edge when thus released.
